[57] CLAIM

The ornamental design for a bottle, substantially as shown.

DESCRIPTION

FIG. 1 is a plan view of a bottle embodying our new design;

FIG. 2 is a front elevational view;

FIG. 3 is a vertical sectional view taken along line 3—3 of FIG. 1;

FIG. 4 is a horizontal sectional view taken along line 4—4 of FIG. 2;

FIG. 5 is a fragmentary vertical sectional view taken along line 5—5 of FIG. 2; and

FIG. 6 is a rear elevational view.
